Filed May 13, 1974, Ser. No. 469,512

Term of patent 14 years

Int. Cl. D6—04

U.S. Cl. D6—157

FIG. 1

FIG. 2

FIG. 1 is a front, top and right side perspective view of a thread cabinet showing my new design with the doors in opened position; and

FIG. 2 is a front elevational view with the doors in closed position.

The rear of the thread cabinet is plain except for the wood graining similar to that shown on the other flat walls of the cabinet. The posts include four vertical rows of pegs equally spaced around the posts.

I claim:

The ornamental design for a thread cabinet, as shown and described.
